United States Patent

Des. 237,581
Patented Nov. 11, 1975

237,581

BOTTLE OPENER OR SIMILAR ARTICLE

Michael J. Pasquale, 115 Grove St.,
Middletown, Conn. 06457

Filed June 27, 1974, Ser. No. 483,880

Term of patent 14 years

Int. Cl. D7—06

U.S. Cl. D8—18

FIG. 1

FIG. 2

FIG. 3

FIG. 4

FIG. 5

FIG. 1 is a side view of a bottle opener showing my new design;

FIGS. 2 and 3 are, respectively, bottom and top plan views thereof; and

FIGS. 4 and 5 are, respectively, left end and right end views of the bottle opener as viewed in FIG. 3.

I claim:

The ornamental design for a bottle opener or similar article, substantially as shown.
